UNITED STATES PATENT OFFICE.

EDWIN C. HAY, OF MONTGOMERY, ALABAMA.

ENGINE.

1,389,505.

Specification of Letters Patent. Patented Aug. 30, 1921.

Application filed June 14, 1919. Serial No. 304,205.

To all whom it may concern:

Be it known that I, EDWIN C. HAY, a citizen of the United States, residing at Montgomery, in the county of Montgomery and State of Alabama, have invented new and useful Improvements in Engines, of which the following is a specification.

This invention relates to internal combustion engines, and the broad object in view, generally stated, is to eliminate many of the working parts now employed in conjunction with the valve mechanism now commonly employed in connection with internal combustion engines, at the same time eliminating the friction due thereto and correspondingly increasing the efficiency of the engine as a whole.

A further object of the invention is to provide an internal combustion engine which, by reason of dispensing with many of the working parts of the valve mechanism, will be light, cheap to manufacture, and economical to run.

With the above and other objects in view, the invention consists in the novel construction, combination and arrangement herein fully described, illustrated and claimed.

In the accompanying drawings:—

Figure 1 is a fragmentary side elevation of a multiple cylinder internal combustion engine embodying the present invention.

Fig. 2 is a fragmentary vertical longitudinal section through the same taken in line with the rotary combined valve and timer shaft.

Fig. 3 is a vertical transverse section taken through the engine in line with one of the timers.

Fig. 4 is a fragmentary plan view of the combined valve and timer shaft.

Fig. 5 is a fragmentary plan view of the engine showing the slots to provide for advancing and retarding the spark.

Figs. 6, 7, 8 and 9 are vertical transverse sections taken in line with one of the valves, showing the different positions of the valve adjacent to the four principal cycles thereof, in each complete revolution of the crank shaft.

In the drawings wherein for the purpose of illustration is shown a preferred embodiment of the invention, the numeral 1 generally indicates an internal combustion engine provided as usual with a plurality of cylinders 2, having pistons (not shown) slidably mounted therein and having con-

nnection with the usual crank shaft through the medium of a plurality of piston rods. As illustrated particularly in Figs. 6 to 8, inclusive, the cylinders 2 are provided with 60 combined inlet and exhaust ports 4.

Specifically, the invention forming the subject-matter of this application includes an elongated plate or cap 3 arranged upon the head of the motor and secured to the 65 same by a plurality of spaced bolts 5. As illustrated in Figs. 6 to 8 the elongated cap or plate 3 and the adjacent portions of the cylinder heads are formed with semi-circular channels arranged in opposed relation for forming a cylindrical bearing 70 opening which rotatably receives a shaft 9.

The shaft 9 is operated at one-half the speed of the engine crank shaft through the medium of a sprocket chain 10 engaged 75 with a sprocket wheel on the crank shaft and a sprocket wheel 11 secured upon the shaft 9.

The timing mechanism for the ignition of the engine is provided for as follows: The 80 shaft 9 is provided at each cylinder with a circumferential groove 12 having a cam shaped or spiral floor 13. The groove 12 terminates at one end in an abrupt radially disposed shoulder 14 and as shown in Fig. 85 4, said shoulder extends upwardly or at an angle to the longitudinal axis of the shaft 9, the purpose of which will hereinafter appear. Each cylinder is provided with a plunger 15 having one end portion arranged 90 in the adjacent groove 14 as shown in Fig. 3, said plunger being pressed outwardly or upwardly by contact with the cam face floor 13 of the groove 12 and thereafter dropping quickly off the shoulder 14 in order to actuate the igniter hereinafter referred to. It

will also be observed that the groove 14 is much wider than the co-acting end of the plunger 15 thereby adapting said plunger 15 to be adjusted longitudinally of the shaft 100 9 for the purpose of varying the time of the spark as will appear. The plunger 15 is connected at its outer end preferably by a ball and socket joint 16 with a rocker arm 17, the latter being pivoted between its ends 105 by means of a ball and socket joint 18 on a supporting post 19 which is securely fastened to the body of the engine. Connected to the outer extremity of the rocker arm 17 by means of another ball and socket joint 20 is a trip rod or push rod 21 which in 110 turn is connected by a ball and socket joint

22 to the arm 23 of the respective rocking element or electrode 24 of the igniter designated at 25 and comprising the other fixed electrode 26, said igniter being of the make 5 and break type. It will now be apparent that the rocking member of the igniter is actuated by the shaft 9 in coöperation with the plunger 15. The upper portion of each plunger 15 passes through a slidable cap 10 or guiding member 27 having a dovetailed sliding connection at 28 with an extension 29 on top of the plate or cap 6 hereinabove referred to. The opening in the cap 6 in which the upper portion of the plunger 15 15 is received, is in the form of a longitudinal slot 30 as shown in Fig. 2. This permits the plunger 15 to be moved lengthwise of the slot 30 or longitudinally of the motor for the purpose of changing the position of 20 the inner end of the plunger 15 with relation to the groove 12 in the shaft 9. By reason of this adjustment of the plunger 15, the inner end of the same is permitted to drop or move inwardly toward the center 25 of the shaft 9 at an earlier or later period in the rotation of said shaft thereby correspondingly retarding or advancing the spark or time of ignition. It will be observed that the radial side of the lobe of each cam thus formed extends obliquely for 30 its entire length with relation to the axis of the shaft and the plunger 15 may be regulated at any desired point along the shoulder 14 for retarding or advancing the spark accurately to the desired extent. All 35 of the sliding caps 27 are connected by a common operating rod 31 which enables all of the plungers 15 to be simultaneously shifted lengthwise of the engine for correspondingly and uniformly advancing or retarding the spark in each and all of the cylinders.

The shaft 9 also constitutes a valve shaft and for that purpose is provided at intervals 45 in the length thereof with enlarged cylindrical portions 33 each of which is formed in the face thereof with a port 34 having an arcuate wall or floor 35. The shaft 9 as a whole is preferably journaled 50 in a casing sleeve 36 placed in the head of the engine, said casing being provided with enlarged portions 37 to receive the enlarged cylindrical valve forming portion 33 described. The enlarged portions 33 are arranged within corresponding enlargements 55 7 and 8. Figs. 6, 7, 8 and 9 illustrate several positions of the valve with relation to the respective cylinders, the direction of rotation of the shaft 9 being indicated by arrows in said figures. In Fig. 6, the valve is shown as beginning its intake stroke, the post of the valve being about to register 60 with the intake port 38, the exhaust port 39 being closed. In Fig. 7, the valve has moved through a quarter of a circle and

the port 4 of the cylinder is closed and cut off from communication with the intake port 38 and also the exhaust port 39. Fig. 8 shows the valve advanced another quarter of a revolution, all of the ports above referred to being closed. The position of the valve in Fig. 8 is the position assumed thereby during the explosion or working stroke of the piston. Fig. 9 illustrates the position of the valve at the beginning of the 75 exhaust stroke, the valve being just about to open the exhaust port 39 and place the same in communication with the combined intake and exhaust port of the cylinder, in the head of the latter. It will thus be seen that each cylinder comprises a combined intake and exhaust port while it and the intake and exhaust passages are controlled by a single rotary valve. This greatly simplifies the construction and operation of 80 the engine, imparts reliability thereto and eliminates considerable waste and friction, thereby increasing the efficiency of the engine.

By means of the construction described 90 use of the ordinary timing mechanism is dispensed with and no spark distributor is required. Each cylinder is timed separately from the remaining cylinder but the proper timing of all these cylinders is insured.

The construction described also reduces the cost of manufacture, and the cost of upkeep. The wiring system is also greatly simplified as compared with the present day ignition system used for automobile and motor vehicle traffic. A large number of working parts are also eliminated and a corresponding amount of friction. The valve mechanism above described does away 100 with the usual cam shaft and other parts incident to the use thereof and the construction also results in a comparatively silent and smoothly operating engine.

I claim:—

1. An internal combustion engine including 110 a plurality of cylinders having combined intake and exhaust ports, a shaft having a plurality of spaced ports adapted for registration with the combined intake and exhaust ports of said cylinders, said shaft being provided with a plurality of grooves having spiral bottom walls thereby forming a plurality of cams, having lobes provided with radial shoulders, said shoulders being disposed obliquely with relation to the axis 115 of said shaft, plungers engaged with the spiral bottom walls of said grooves, igniting devices associated with said plungers, and means whereby said plungers may be moved together longitudinally of said shaft whereby the spark of said igniting device may be retarded or advanced to the desired extent.

2. An internal combustion engine including 125 a plurality of cylinders having heads, an elongated cap arranged upon said cylin- 130

der heads, said cylinders being provided with combined intake and exhaust ports, a shaft arranged between said elongated cap and said cylinder heads and provided with 5 ports adapted for registration with the ports of said cylinders as the shaft rotates, said shaft being provided with a plurality of grooves having spiral bottom walls and radial shoulders, a plurality of plungers en- 10 gaging the spiral bottom walls of said grooves, said elongated cap being provided with spaced enlargements having elongated slots receiving said plungers, heads slidably mounted on said enlargements and connected 15 to said plungers, means for moving said heads longitudinally of the engine for adjusting said plungers with relation to the radial shoulders of said grooves, said radial shoulders being extended obliquely with 20 relation to the axis of said shaft whereby the plungers may be positioned longitudinally of said shoulders, and an igniting de- vice operated by said plungers.

3. In an internal combustion engine, the

combination of a cylinder, a combined valve 25 and timer shaft extending at a right angle to said cylinder and connected by actuating means with the engine crank shaft, a valve body on said shaft having a port forming both an inlet and an exhaust port and adapt- 30 ed to register with a corresponding port in the cylinder, said shaft being further formed with a groove extending around the same and having a cam shaped floor, a make and break igniter connected to said cylinder, 35 and igniter actuating means comprising a plunger having its inner end working against the cam faced floor of said groove, a rocker arm having a ball and socket connec- 40 tion with said plunger, a rocker arm having a ball and socket connection with the latter, and a push rod having a ball and socket connection at one end with said rocker arm and a corresponding connection at the other end with a movable element of said 45 igniter.

In testimony whereof I affix my signature.
EDWIN C. HAY.
